VIBRATO DEVICE FOR GUITARS

Clarence L. Fender, Fullerton, Calif., assignor to Fender Electric Instrument Company Inc., Fullerton, Calif., a corporation of California

Filed Mar. 17, 1965, Ser. No. 84,329

Term of patent 14 years

(Cl. D56—1)

FIGURE 1 is a perspective view of a vibrato device for guitars, embodying my new design;

FIGURE 2 is a top plan view thereof;

FIGURE 3 is a side elevation; and

FIGURE 4 is an end elevation, as viewed from the left in FIGURE 3.

The side of the horizontal cylindrical bar which is not shown in FIGURE 4 is identical to the side shown therein. The bottom of the horizontal plate is plain, the mounting means for such plate being unshown.

The dominant features of the design reside in the portions shown in full lines.

I claim:

The ornamental design for a vibrato device for guitars, substantially as shown and described.
